UNITED STATES PATENT OFFICE

JOSEPH F. KELLER, OF NEW YORK, N. Y., ASSIGNOR, BY MESNE ASSIGNMENTS, TO PRATT & WHITNEY COMPANY, OF HARTFORD, CONNECTICUT, A CORPORATION OF NEW JERSEY

FLEXIBLE SHAFT MACHINE ATTACHMENT

Application filed October 12, 1929. Serial No. 399,378.

This invention relates more particularly to an improvement for a flexible shaft machine of the type shown and described in Bachmann Patent No. 1,575,307 of March 2, 1926. The attachment comprises a tubular switch arm extending outward from the pivoted bracket supporting the motor and its connections to the flexible shaft, this tubular arm being provided with means at its outer end for supporting the flexible shaft and a switch for controlling the motor by wiring connections through the tubular arm, and a counterweight extending from the bracket in the opposite direction from said tubular arm is provided for counterbalancing the latter.

Flexible shaft machines as now known to the trade are provided with a supporting stand upon which a bracket is pivotally mounted, carrying the motor and connections therefrom for driving the flexible shaft, the latter extending outwardly from the pivoted bracket, substantially at right angles to the pivot thereof. The motor and driving connections therefrom to the flexible shaft are usually arranged with reference to the pivotal support so as to substantially balance with the flexible shaft extending outward from the pivotal bracket.

In order to improve the flexible shaft machine shown herewith, however, and particularly with large machines, it is desirable to facilitate operation thereof by locating the switch at a distance from the motor and in a more convenient position in relation to the flexible shaft, so as to bring it within easy reach of the operator handling the grinding wheel or other device at the end of the flexible shaft, and with the larger type of machines the flexible shaft is heavy so that an auxiliary support therefor will assist the operator. In cooperation with the switch arm and as a part of this additional equipment to the flexible shaft machine, there is provided a counterweight extending in the opposite direction to balance the switch arm and flexible shaft support.

The object of the present improvement, therefore, is to provide the flexible shaft machine of the type referred to with an arm

for partially supporting the flexible shaft and a switch connected with the motor for controlling the same, and as part of the equipment, providing a counterweight to extend in the opposite direction from the switch arm for counterbalancing the latter. 55

The present improvement is more particularly shown in the accompanying drawing, in which Fig. 1 represents a well known type of flexible shaft machine equipped with the improvement, and Fig. 2 is an end view of the bracket at the end of the switch arm for supporting the flexible shaft. 60

Referring to the drawing, a flexible shaft machine of suitable construction is supported upon a base or stand provided with an upright pillar A which, in the present instance, carries a fork B, in which the supporting bracket C is pivoted at D. The bracket C is arranged to support the motor E and its driving connections to the flexible shaft, the motor through the pulleys F and G being adapted to drive the usual flexible shaft in its sheath H which extends outward substantially at right angles to the pivot D. 70 75

In order to provide partial or auxiliary support for the outwardly extending flexible shaft and more particularly for conveniently locating a switch near the operator for controlling the motor, an arm K, preferably formed of steel tubing and supported from the upper portion of the pivoted bracket C by being inserted into a socket at L, where it is secured by a set screw M. The lead wires N from the line to the motor are adapted to pass through the tube K to an electric switch O mounted on a casting P at the outer end of the tubular arm K, substantially as shown in Fig. 1. The casting P is preferably provided with a downwardly extending member in the form of a ring Q, through which the flexible shaft H extends, so that it may be partially supported and prevented from making too sharp a bend near the drive end. 80 85 90 95

When the switch arm K is mounted on the supporting bracket C, it is found desirable to provide a counterbalance therefor, and for this purpose, an arm or rod R is preferably mounted in a boss or lug S, or other 100

suitable projection extending from the bracket C, and is secured therein by a set screw T. In the present instance there is mounted upon the rod R, an adjustable counterweight U, provided with a thumb screw V, for securing the counterweight in any adjusted position.

The operation of the improvement is simple, the switch supporting arm K is mounted in the socket L on one side of the bracket pivot D and the counterweight U and rod R are attached on the opposite side for counterbalancing the switch arm K, as indicated in Fig. 1. The advantage of placing the switch at the end of the rod K will be evident, when it is realized that the operator is usually holding the outer end of the flexible shaft, which contains the usual hand piece for the grinding wheel or other tool being operated, and, therefore, by placing the switch on the end of the arm K, it is in more convenient reach for the operator in starting and stopping the motor. In addition to serving as a switch arm, since the flexible tube and its armor are relatively heavy, it is found desirable to partially support the latter from the arm K by means of the ring Q, thus further assisting and making it more convenient for the operator in handling the hand piece at the end of the flexible shaft.

In providing this improved attachment to the flexible shaft machine, it will be understood that it is not intended to limit the construction to that specifically shown and described, for obviously, various modifications therein may be made without departing from the spirit and scope of the invention.

I claim:

An attachment for flexible shaft bench grinders wherein a supporting stand is provided with a bracket pivotally mounted thereon and adapted for pivotally supporting the motor and its driving connections to the flexible shaft, comprising a tubular arm extending outward from said bracket above and in the direction of the flexible shaft, means for detachably securing the tubular arm to the bracket, a bracket provided with a depending ring at the outer end of said tubular arm, said ring being adapted to support the flexible shaft and permit lateral and up and down movement thereof, an electric switch mounted on said tubular arm bracket above the ring, wiring connections extending from said switch through the tubular arm to the motor for controlling the same, a counterweight arm adapted to extend from said motor supporting bracket in the opposite direction from said tubular switch arm, means for removably attaching the last named arm to the bracket and an adjustable weight on said counterweight arm for counterbalancing the tubular switch arm.
